HOSE AND SUPPORTER

Filed April 25, 1932

UNITED STATES PATENT OFFICE

2,035,469

HOSE AND SUPPORTER

Eugene Franklin Gaines, Merion, Pa., assignor to
 H. Birchard Taylor and Chester W. Larner,
 both of Philadelphia, Pa.

Application April 25, 1932, Serial No. 607,309

1 Claim. (Cl. 2—240)

My invention relates to hosiery units comprising the hose proper and means for supporting or holding them in place, whereby a unit, comprising the hose proper and structure wholly or partly functioning in lieu of the usual detachable garter, may be laundered without disassembly. In accordance with my invention there is attached to or made a part of the hose proper one or more members or elements, extending upwardly from the hose, and preferably yielding or elastic longitudinally of the leg, and constituting means for connecting the hose to a leg-embracing band-like structure which is elastic or yields circumferentially of the leg.

More particularly the connecting member is a knitted fabric, preferably transversely ribbed, and in any event elastic or yielding in a direction longitudinally of the leg.

Further in accordance with my invention the leg-embracing band is wholly or in part a knitted, preferably ribbed, fabric which is elastic or yields circumferentially of the leg.

More particularly in accordance with my invention the aforesaid fabric, utilized for the connecting member or the leg-embracing band, is comprised, at least in part, of highly elastic yarn, such for example as may be formed by spinning cotton, silk, wool or the like upon a core or thread of highly elastic rubber, whereby the connecting member or the leg-embracing band is of greater elasticity than that employed in garters commonly used in the art in order that clasps and adjustments may be dispensed with, and a supporter produced that will easily pass over the foot and fit any size or shape of leg comfortably and efficiently.

My invention resides in a hosiery unit of the character hereinafter described and claimed.

For an illustration of one of the various forms my invention may take, reference is had to the accompanying drawing, in which:

Figs. 1 and 2 are front and side views, respectively, of a hosiery unit in accordance with my invention;

Fig. 3 is an enlarged front view of the supporter shown in Figs. 1 and 2.

Referring to Fig. 1, T is the top of the hose H, and, as usual, is preferably of knitted vertically ribbed fabric whereby it is resilient or yielding circumferentially of the leg. The top T may, however, be knitted plain, or be of a structure of low yield or low elasticity.

The leg-encircling band structure consists in this example of a permanently closed band that is longitudinally yielding or resilient in a direc-

tion circumferentially of the leg, and for this purpose may be constructed of any suitable material. In the example illustrated the band B₂ is a knitted vertically (transversely) ribbed elastic fabric.

To the element B₂ is secured, by stitching or equivalent means, the upper end of each of the one or more connector members C, of knitted horizontally (transversely) ribbed elastic fabric, generally of the character of the fabric of which band member B₂ is made. Each element C is similarly attached by stitching or equivalent means at its lower end to the upper end of the top T of the hose. When two members C are employed as illustrated, they are so spaced from each other at the upper edge of the top T that upon the circumferential extension of the top T when upon the leg, the elements C, C will be suitably spaced from each other as indicated in Fig. 3.

The yielding or elasticity of the connector members C longitudinally of the leg is of advantage in that it accommodates the hosiery unit to fit legs of different sizes and proportions, permitting the band structure which encircles the leg always to be in suitable position above the calf and at suitable incline, as indicated in Fig. 2.

To procure or permit suitable incline of the band structure when upon the leg, either end, generally the upper end, or both ends, of each of the connector members C may be to suitable extent inclined, or cut on a slant, at an angle other than 90° with the side edges of the member C. Similarly, the lower ends of each member C may be cut at such angle to its sides as to accommodate the top T of the hose.

Where substantially the entire band is yielding or elastic, it adjusts itself to suitable incline upon the leg. The upper ends of the connector members C are at suitable incline to their sides where attached to the band B₂.

The material or fabric for the connector elements C, or the band structure B₂ may be increased as to its elasticity or yielding qualities by combining therewith edge or marginal elements of rubber or the like, particularly in the form of elastic tape or braid. Preferably, however, the extra resiliency or elasticity of the fabric is procured by knitting or incorporating therein several courses, indicated by the narrow areas or bands L in the drawing, of any special yarn which is unusually resilient or yielding. These courses themselves may also be ribbed in conformity with the knitted structure of the body of the material itself. For such purpose

there is preferably used a resilient yarn comprising a core or thread of highly resilient rubber, or equivalent, upon which is wound or spun fibers of cotton, wool, silk, rayon or any other suitable material. The weaving within the fabric of this special yarn or elastic thread imparts thereto an unusual resiliency of advantage in a hosiery unit of the character described. In the case the special yarn comprises a thread or core of rubber, it may be of a known type withstanding temperatures upwardly of 212° F. and which also withstands numerous washings. In knitting the aforesaid elastic fabric the special elastic thread or spun yarn is substituted at any suitable regular intervals for the yarn constituting the remainder of the fabric. The special highly elastic thread or yarn may be of the character known as "Lastex", and generally of the character described in Letters Patent of the 20 United States, Nos. 1,822,847 and 1,545,257.

The edges of the members C and B₂ of the elastic or resilient fabric described may be suitably bound, as by suitable stitching which will not materially interfere with the elasticity of the 25 fabric itself. For such binder stitching there may be utilized the elastic thread or yarn herein described in producing the elements L, which themselves may be at the edges or constitute marginal edges of the members C or B₂. Similarly stitching which does not materially interfere with the elasticity of the fabric may be utilized for attachment of the members C to the elastic element B₂.

In attaching the parts to each other, particularly connector members C to the band structure B₂, or to the top T, they may be stitched to each other in overlapping relation. It is preferred, however, that the parts abut in non-overlapping relation; when so abutting they may be attached 40 to each other by stitching forming so-called flat-lock or bar-lock seams.

A hosiery unit of the character herein described has the advantage that it may as such and without disassembly be washed or laundered. The hose supporting or garter elements of the unit, such as the connector members C and band member B₂, are of a character which withstand numerous washings without disassembly from the hose itself. 5

The materials for the connector members C and the leg-encircling band structure may be 10 anything suitable for the purposes described. It is preferred, however, that they be substantially free of such usual garter materials as rubber, rubber elastic and the like, which do not well withstand numerous washings or elevated temperature. 15

The fabric for the members B₂ and C may be of any suitable character provided it be sufficiently elastic; it may be of knitted, woven or other type, and either ribbed or not. Furthermore, the fabric for those members may be woven or knitted, wholly or in part, of the extra elastic thread or yarn, of the character hereinbefore described, utilized for the parts or fabric components L. 20 25

What I claim is:

A hosiery unit comprising, in combination, a hose, a continuous leg-encircling member spaced from the top of said hose and consisting of a band of highly elastic material having its ends 30 permanently connected together, and two suspension members each consisting of a strip of highly elastic material having their upper ends permanently connected to the leg-encircling member and their lower ends permanently connected to the top of the hose, the distance between said suspension members when measured around the front of the leg being substantially less than that measured around the back of the 35 leg. 40

EUGENE FRANKLIN GAINES.
